DESIGN FOR A BOTTLE

Fred R. Hoch, Norton, Mass., assignor to T. J. Holmes Co. Inc., Chartley, Mass., a corporation of Massachusetts

Application September 16, 1941, Serial No. 103,370

Term of patent 7 years

To all whom it may concern:

Be it known that I, Fred R. Hoch, a citizen of the United States, residing at Norton, in the county of Bristol and Commonwealth of Massachusetts, have invented a new, original, and ornamental Design for a Bottle, of which the following is a specification, reference being had to the accompanying drawing forming a part thereof, in which

Figure 1 is a plan view of a bottle showing my new design;

Fig. 2 is a side elevational view of said bottle; and

Fig. 3 is a bottom view of the bottle.

The circumferential surface of the bottle is divided into quadrants by equally spaced substantially vertical rows of beads and the ornamental pattern as shown in one quadrant in Fig. 2 is repeated in regular succession in each quadrant around the circumference of the bottle.

I claim:

The ornamental design for a bottle, substantially as shown and described.

FRED R. HOCH.
